UNITED STATES PATENT OFFICE.

WILLIAM L. DAYTON AND JOHN M. SCOTT, OF FORT WORTH, TEXAS.

WELL-DRILLING MACHINE.

1,301,915.

Specification of Letters Patent. Patented Apr. 29, 1919.

Application filed June 22, 1918. Serial No. 241,325.

To all whom it may concern:

Be it known that we, WILLIAM L. DAYTON and JOHN M. SCOTT, both citizens of the United States of America, residing at Fort Worth, in the county of Tarrant and State of Texas, have invented certain new and useful Improvements in Well-Drilling Machines, of which the following is a specification.

10 Our invention relates to well drilling machines, construction and mine hoisting machines, freight and passenger elevators, and various machines using derricks and cranes, and the object is to provide improvements 15 and attachments which are relatively simple in construction and operation and which is provided with certain swinging gravity-actuated devices by which the machine can be operated with much less driving power 20 and expense and to provide improvements by which the machine is greatly increased in efficiency. Other objects and advantages will be fully explained in the following description and the invention will be more 25 particularly pointed out in the claims.

Reference is had to the accompanying drawings which form a part of this application.

Figure 1 is a side elevation of the machine. Fig. 2 is a side elevation of the machine, being the opposite side from that shown in Fig. 1. Fig. 3 is a plan view of the machine. Fig. 4 is a detail view of the cam arm and operating crank with rollers. 30 Fig. 5 is a detail view of one of the gear-controlling levers. Fig. 6 is a detail view of a variation in the driving gear. Fig. 7 is a detail view, showing a variation in the operating cam for the walking beam. 35 Similar characters of reference are used to indicate the same parts throughout the several views.

The machine is provided with a rectangular upright frame having lower longitudinal beams 1 and 2 and upper longitudinal beams 3 and 4. The beams 3 and 4 are supported by corner uprights 5, 6, 7, and 8 which are attached to the lower and upper longitudinal beams. At the work end of the machine, 40 the beams 5 and 7 are braced by a cross-bar 9 which is attached to both uprights 5 and 7. The uprights 5 and 7 are further braced by cross-bars 10. At the power end of the machine, the uprights 6 and 8 are braced by 45 cross-bars 11. The cross shafts hereinafter

set forth will further brace the uprights 5, 6, 7, and 8.

The machine is mounted on a wheeled truck, being supported thereon by the side beams 1 and 2.

For drilling, a master wheel 12 is rigidly mounted on a shaft 13 which is journaled in the uprights 14 which are rigid with the frame members 1 and 3 and 2 and 4. Means are provided for driving the wheel 12. The 65 wheel 12 is provided with internal gear teeth or cogs 15. A power shaft 16 is journaled in uprights 6 and 8 and provided with a power pulley 17 rigid therewith. A balance wheel 18 is mounted on the other end of 70 the shaft 16. A pinion 19 is rigid with shaft 16 for transmitting the power from this shaft. The pinion 19 meshes with and drives a cog wheel 20 which is rigid with a 75 shaft 21. The shaft 21 carries a pinion 22 rigid therewith. The pinion 22 meshes with and drives the internal gear wheel 15 for elevating the drill 23. The master wheel 12 is a cog wheel and meshes with and drives a pinion 24. The pinion 24 is rigid with a 80 shaft 25 and drives this shaft when the pinion 24 is in mesh with the master wheel 12. The shaft 25 carries a spool 26 rigid therewith for winding the cable 27 which has one end attached to wheel or spool 26 85 and the other end attached to the drill 23. The cable 27 runs from the spool 26 under a shaft 28 which is provided with an anti-friction roller 29. The cable 27 then runs over an idler 30 and then down under an 90 idler 31 and then up over an idler 32 and then down to the drill 23. This describes the course of the cable and the means for operating the same for elevating the drill.

When the drill has been mounted in the 95 manner described, it is actuated by the following described mechanism. The pinion 24 is thrown out of mesh with the cog wheel 12 by a hand lever 33 which is provided with a fulcrum 34 pivoted in a bearing member 35 which is attached to the cross-bar 9. The bearing member 35 has notches 36 in the upper edge and a spring-actuated dog 37 carried by the lever 33 engages one of the notches 36 to hold the lever 33 in position. A link bar 38 is pivotally connected to the lever 33 by a pivot bolt 39 which projects through the bearing member 35 and the bearing member 35 has a curved slot 40 for the movement of the pivot bolt 39. The 100 105 110

link bar 38 is pivotally connected to a bell-crank lever 41 which is fulcrumed on a bar 42 and which engages the shaft 25 for throwing the pinion 24 in and out of mesh 5 with the cog wheel 12. The dog 37, when in one notch 36, will cause the levers to hold the wheel 24 in mesh with the cog wheel 12, and when in the other notch 36, will cause the levers 33 and 41 to hold the wheel 24 10 out of mesh with the wheel 12. The upright 14 has an elongated bearing opening to permit adjustment of the shaft 25. At the required time the wheel 24 is thrown out of mesh with the wheel 12 so that the drill can 15 be actuated.

The roller 30 is carried by a swinging link 43 and this link is carried by a walking beam 44 which is fulcrumed in uprights 45 which are attached to the beams 1, 3, 2, and 20 4. The walking beam 44 carries a cam arm 46 rigid therewith. A crank 47 is rigid with shaft 13 and carries an antifriction roller 48. The cam arm 46 is attached to the walking beam 44 by arms 49. When the 25 shaft 13 is driven by the wheel 12, the crank 47 with its roller 48 will engage the cam arm 46 and so rock the beam 44 which will by means of the link 43 and roller 30 lift the drill 23 and let the drill fall at regular intervals. 30

A swinging weight 50 is used to coöperate with the driving mechanism for actuating the drill. The weight 50 is pivotally connected to the walking beam 44 by means of 35 a bar 51 which has a lug pivotally connected to arms 53 which are attached to the beam 44. A bell-crank lever 54 is fulcrumed on the beam 44 and pivotally connected to the link 43 and a rod 55 is pivotally connected 40 to the lever 54 and the bar 51 above its pivotal connection with the beam 44. In operation, the crank 47 will engage the cam arm 46 and thus bear the end of the walking beam 44 downwardly at that end. This will 45 raise the link bar 43 and thus elevate the drill. While this operation is going on, the drill will be pulling on the lever 54 and the lever 54 will pull on the rod 55 and this rod will pull on the bar 51 and tend to raise the 50 weight 50 and does raise this weight so that the weight 50 will be elevated by the weight of the drill. The weight 50 will thus co- 55 operate with the cam operated end of the walking beam to aid in raising the working end of the beam which action will elevate the drill. As the weight is gradually raised the leverage will be increased and the work accomplished by the weight will be correspondingly increased. As the bar 51 is approaching a position to be in line with the beam 44, the leverage is being automatically increased and this increase in leverage tends to balance the weight or load of the drill. The driving mechanism can be operated 60 with much less power than would be re- 65

quired without the weight. When the roller 48 passes far enough it will release the cam arm 46, the work end of the beam 44 will drop downwardly and the weight 50 will also drop so that the work end of the beam 44 70 will drop more freely. This lets the drill fall to do its work.

A brake mechanism is provided to regulate the speed of the machine. A brake wheel 56 is mounted on shaft 13 and a strap brake 57 75 is passed around the wheel 56 and attached to an upright bar 58 which is attached to the beams 1 and 3. The other end of the strap 57 is attached to a brake lever 59 which is fulcrumed on the upright 58. The lever 59 80 extends back to the work end of the machine for the convenience of the operator and is retained in place by a bracket 60. The lever 59 is held in the elevated inoperative position by a spiral spring 61. The brake is operated 85 by bearing down on the end 62 of the lever. When it is released, the spring 61 replaces the lever to inoperative position. When the machine is drilling the spool 26 is locked against revolving by the worm pinion 72 90 hereinafter described.

When the beam 44 is not to be used in drilling, it is locked rigid in a horizontal position by an arch lock 63 which is pivotally mounted on the beams 3 and 4. This 95 stop or lock is actuated by a lever 64 which is fulcrumed on the inside of the upright 5 and pivotally connected to a link bar 65 which is pivotally connected to a crank 66' which is rigid with the lock 63. The stop 100 can be operated by using the lever 64. The crank 47 is loosely mounted on the shaft 13 and is locked thereto by clutch members 65 and 66. Simultaneously with the locking of the beam 44 against movement the crank 105 47 is released from shaft 13 by shifting the clutch member 66 out of mesh with clutch member 65. This is done by a bell-crank lever 67 which is fulcrumed on a bracket 68. One arm of the lever 67 engages a collar 69 110 which is integral with the clutch member 66 and the other arm of this lever is connected to the crank 66' by a link bar 70. The clutch members are held normally in mesh with each other by a spring 71. When the beam 115 44 is locked against movement and the clutch members 66 and 67 are disconnected the machine is used for bailing the well or for placing or replacing casing or for other purposes. 120

The length of the stroke of the drill is varied by varying the length of the cable 27. Means are provided for winding the cable 27 more or less on the spool 14. The pinion 24 is thrown out of mesh with cog wheel 12 125 by lever 33, as above described. At the same time the pinion 24 is thrown out of mesh with cog wheel 12, the pinion 24 is thrown in mesh with a worm wheel 72 which is provided with a shaft 73. By means of the 130

pinion 24, worm wheel 72, shaft 73, and a crank 74 for shaft 73, the spool 26 can be revolved in either direction for making the cable 27 throw more or less to vary the stroke of the drill, and for feeding the cable to the drill as the drill goes deeper.

When the machine is not being used for actuating the drill, the speed of the wheel 12 and shaft 13 may be driven much faster.

10 A cog wheel 75 is rigid with the wheel 12. The pinion 22 which, when the machine is drilling, engages the internal cog wheel 15, may be shifted to engage the cog wheel 75 which is much smaller in diameter than the internal gear wheel 15. This will increase the speed of the shaft 13 without increasing the speed of the shaft 21. The shifting of the pinion 22 is accomplished by a lever bearing 76 which is fulcrumed on a bracket 20 77 and which engages the hub of pinion 22 loosely. The lever bearing 76 is actuated by a link bar 78 which is pivotally connected thereto and pivotally connected to an upstanding crank 79 which is rigid with a 25 rocker shaft 80. The shaft 80 is actuated by a link bar 81 which is pivotally connected to an upstanding crank 83 which is rigid with shaft 80 and pivotally connected to a lever 82 which is a duplicate in construction of 30 the lever 33, shown in Fig. 5, and has similar equipment. The lever 82 can be thus used to shift the pinion 22 into mesh with internal gear wheel 15 or into mesh with the pinion 75 for changing speed and for reversing purposes.

The machine is provided with a spool or drum 84 which is journaled in bearings 85 and 86. The spool 84 is driven by a pinion 87 which is adapted to be thrown in mesh 40 with cog wheel 12. The bearing 86 has an elongated bearing opening for the spool shaft 89 and a link bar 90 is pivotally connected to the shaft 89 and pivotally connected to a lever 91 which is fulcrumed on 45 the upright 7. The lever 91 may be used to throw the pinion 87 in mesh with the wheel 12 for bailing the well. The lever 91 will hold the shaft 89 in whatever position that may be required.

50 The variation shown in Fig. 6 consists in substituting a friction drive for the pinion 22 and co-operating gearing. A friction pinion 92 is provided and an internal friction wheel 93 takes the place of gear wheel 15 and a friction pinion 94 takes the place of the pinion 75.

The variation shown in Fig. 7 consists in using wrist pins 95 instead of the crank 47 on shaft 13. The wrist pins may be carried 55 by the master wheel. The cam arm 46' with the attaching arms 49' is attached to the walking beam 44 and the devices operate in the same manner, as the arm 46 and crank 47 with the rollers 48.

65 Various other changes in the construction,

proportion, and arrangement of the several parts may be made without departing from our invention.

What we claim, is,—

1. A well drilling machine having a 70 frame, a derrick pivotally mounted at the work end of said frame, a roller carried thereby, a cable spool journaled in said frame, a cable attached thereto and mounted on said roller and a drill attached to said cable, and means for operating said cable consisting of a walking beam fulcrumed on said frame and carrying a cam arm, means on one end of said beam for pulling said cable and a weight on the other end of said beam for co-operating with an actuating means, and an actuating means for alternately engaging and releasing said cam arm for actuating said beam.

2. In a well drilling machine provided 85 with a frame having a derrick at one end provided with a roller, a cable spool journaled in said frame, a cable attached thereto and mounted on said roller and a drill carried by said cable, a walking beam fulcrumed 90 on said frame and carrying at one end swinging means for actuating said cable and at the other end a swinging weight operatively connected to said swinging actuating means, and means for rocking said walking beam.

3. In a well drilling machine provided 95 with a frame having a derrick at one end provided with a roller, a cable spool journaled in said frame, a cable attached thereto and mounted on said roller and a drill carried by 100 said cable, a walking beam fulcrumed on said frame and carrying a bell crank lever, a swinging bar pivotally connected to said lever and carrying a roller engaging said cable, a swinging weight carried on the other end of said beam and operatively connected to said lever, and means for rocking said beam.

4. In a well drilling machine provided 110 with a frame having an idler mounted in one end, a cable spool journaled in said frame, a cable attached thereto and mounted on said roller and a drill carried by said cable, a walking beam fulcrumed on said frame, a bell crank lever fulcrumed on one 115 end of said frame, a swinging link bar carried by said lever and carrying a roller engaging said cable, a bar pivotally mounted on the other end of said beam and a weight carried by said bar, means for rocking said 120 beam, and means operatively connecting said bell-crank lever and the last mentioned bar.

5. In a well drilling machine provided 125 with a frame, a derrick mounted on the work end of said frame and a roller carried by said derrick, a cable spool journaled in said frame, a cable attached to said spool and mounted on said roller and a drill carried by said cable, a walking beam fulcrumed on 130

said frame, a cam arm rigid therewith, an actuating shaft journaled in said frame and a crank mounted on said shaft and provided with rollers for engaging said cam arm, 5 means for driving said shaft for actuating said beam, a bell crank lever fulcrumed on the work end of said beam, a swinging bar pivotally connected to said lever and provided with a roller engaging said cable between said spool and the roller on said derrick, a radial bar pivotally connected to the other end of said beam and having an arm projecting above said beam and a weight carried by the lower end of said radial bar, 10 and a rod connecting said lever and said projecting arm whereby said weight coöperates with the driving means for actuating said walking beam.

6. In a well drilling machine provided 20 with a frame having a derrick at the working end provided with a roller, a cable spool journaled in said frame, a cable attached thereto and mounted on said roller and a drill carried by said cable, a walking beam fulcrumed on said frame and provided with a swinging arm carrying a roller engaging said cable between said spool and said first named roller, means for actuating said walking beam, and a weight and a swinging bar 30 carrying said weight and pivotally connected to the other end of said walking beam whereby said weight coöperates with said actuating means for rocking said beam.

7. In a well drilling machine provided 35 with a frame having a cable directing roller at the work end of said frame, a cable spool journaled in said frame, a cable attached thereto and mounted on said roller, a walking beam fulcrumed on said frame and provided with a swinging arm carrying a roller engaging said cable between said spool and said cable directing roller, a cam arm rigid with said beam, an actuating shaft and a master wheel rigid with said shaft and provided with internal and external cog wheels 45 and a pinion rigid therewith, gearing for driving said actuating shaft including a shiftable pinion, means carried by said actuating shaft for actuating said cam arm, means for causing said shiftable pinion to engage said internal cog wheel or said pinion, and means for varying the stroke of the drill carried by said cable consisting of a pinion adapted to engage said external cog wheel 50 mounted on said spool shaft for driving the same, and means for driving the last named pinion when thrown out of mesh with said external gear wheel.

8. In a well drilling machine provided 60 with a frame having a cable directing roller at the work end of the machine, a cable spool journaled in said frame, a cable attached thereto and mounted on said roller and carrying a drill, a walking beam fulcrumed on said frame and provided with a

swinging arm carrying a roller engaging said cable between said spool and said cable directing roller, gearing for actuating said beam for operating said drill, means for locking said beam against movement when 70 said machine is not drilling, gearing for operating said cable when used for other purposes than drilling, and means for shifting the gearing of the machine for different purposes. 75

9. In a well drilling machine provided with a frame having a cable directing roller at the work end of the machine, a cable spool journaled in said frame, a cable attached thereto and mounted on said roller 80 and carrying a drill, a master wheel provided with operative connections with said cable for operating the same, a pinion for driving said spool meshing with said master wheel, means for throwing said pinion 85 out of mesh with said master wheel, and a worm pinion for operating said spool driving pinion when not in mesh with said master wheel.

10. In a well drilling machine provided 90 with a frame, a walking beam fulcrumed on said frame, a drill operating cable, a working connection on one end of said walking beam with said cable for actuating said cable, means for actuating said walking beam, and a swinging weight on the other end of said walking beam for balancing the load carried by said cable. 95

11. In a well drilling machine provided with a frame, a walking beam fulcrumed 100 on said frame, a drill operating cable operatively connected with said machine, a working connection on one end of said beam with said cable whereby said beam actuates said cable, means for operating said walking beam, a weight, and a swinging bar 105 pivotally connected to the other end of said beam and carrying said weight at the other end for automatically increasing the balancing effect during a stroke of the drill. 110

12. In a well drilling machine provided with a frame, a walking beam fulcrumed on said frame, a drill operating cable operatively connected with said machine, a working connection on one end of said beam with said cable whereby said beam operates said cable, means for actuating said walking beam, a bar pivotally connected to the other end of said beam and provided with an upwardly projecting arm, a weight carried by the lower end of said bar, and a bar pivotally connected to said working connection and pivotally connected to said upwardly projecting arm whereby said weight automatically balances the load 115 120 carried by said cable.

13. In a well drilling machine provided with a frame having a cable directing roller at the work end of the machine, a cable spool journaled in said frame, a cable at- 130

tached thereto and mounted on said roller and carrying a drill, a master wheel provided with operative connections with said cable for operating the same, a pinion for 5 driving said spool meshing with said master wheel, means for throwing said pinion out of mesh with said master wheel, a brake wheel rigid with said master wheel, a strap brake attached to a rigid portion of said 10 frame and engaging said wheel, and a lever fulcrumed on said frame with one end attached to said brake and the other end projected out at the work end of said machine.

14. In a well drilling machine provided 15 with a frame, a walking beam fulcrumed on

said frame, a drill operating cable, a working connection on one end of said walking beam with said cable for actuating said cable, a master wheel and shaft therefor for actuating said walking beam, a swinging 20 weight on the other end of said walking beam for balancing the load carried by said cable, a brake wheel rigid with said master wheel, a strap brake engaging said brake wheel, and a lever for actuating said brake. 25

In testimony whereof, we set our hands,
this 15th day of June, 1918.

WILLIAM L. DAYTON.
JOHN M. SCOTT.
